UNITED STATES PATENT OFFICE.

ANTHONY BERNARD TUBINI, OF LONDON, ENGLAND.

PROJECTILE.

SPECIFICATION forming part of Letters Patent No. 684,653, dated October 15, 1901.

Application filed November 20, 1900. Serial No. 37,151. (No model.)

To all whom it may concern:

Be it known that I, ANTHONY BERNARD TUBINI, a subject of the Queen of Great Britain, residing at 18 Old Broad street, London, England, have invented certain new and useful Improvements in or Connected with Projectiles, of which the following is a specification.

The object of my invention is to apply or combine with an ordinary bullet, shot, shell, and other like projectiles an illuminating agent in such manner that the illuminating agent will be ignited either at the end of the journey of the projectile or during the transit of the projectile through the air at a predetermined distance, the ignition being caused either by concussion, time-fuse, or other means, thus enabling movements of troops, places, or other objects to be distinguished at night or in the dusk.

20 The illuminating agent may be magnesium or any other known substance capable of ignition by concussion or time-fuse or other means.

When the projectile is of elongated-bullet shape, I prefer that the illuminating agent be attached to the base, and the casing holding the illuminating agent may be slotted or perforated or so made or wadded that when the ignition takes place the explosion or the flame 25 will open the hole or eject the wad and illuminate the place at which the bullet struck, or such illuminating agent may be protected by a waterproof material capable of fusion or ignition of the illuminating agent, or if it be 30 desired that a time-fuse be employed it may be arranged that the illuminating agent be ignited before the projectile has finished its travel and by explosion or other means free itself from the projectile, and so illuminate the 35 place around which it left the projectile, the chief feature of the invention being the combination of the illuminating agent with an ordinary bullet, shell, or like projectile, the illuminating agent being ignited either during 40 the travel of a projectile or at the end of its journey to enable places or movements of an enemy to be inspected during darkness.

In the annexed sheets of drawings Figures 1 to 7 indicate several examples, in sectional elevation, of how my invention can be carried 45 into effect.

Fig. 1 indicates in longitudinal section a

projectile in which the magnesium or other illuminating agent A is placed within a recess made in the body of the projectile or surrounded by a protector or casing B, which becomes ignited or torn asunder when the magnesium is fired. The firing is effected by the striking of the projectile against an obstacle, this flattening the nose of the projectile and acting upon the rod C, arranged within the projectile, this rod C striking the fulminate D, which in turn sets fire to the magnesium A. The firing is effected by practically the same means in all the figures of the drawings. 55

Fig. 2 is a similar view to Fig. 1, but the fulminate is in connection with a fuse E, which communicates with the magnesium, so that the illumination will not take place immediately. 60

Fig. 3 is a longitudinal section of a projectile in which the fulminate D is in connection with a time-fuse F, this in time communicating with the magnesium A, which in this case is of rope or band form, coiled around the projectile and incased with a composition to support its steady combustion. 70

Fig. 4 is a similar view of a projectile in which the rod C acts upon two other rods C' C" for exploding the fulminate in two places. 80 The base of the projectile in this case is provided with a screw G for affixing to the projectile.

Fig. 5 is a longitudinal section of a projectile having a coil of magnesium wire or rope incased in a preparation to insure steady combustion, the base being secured to the projectile. 85

All the above figures have the illuminating agent incased in a groove on the outside of the projectile, but at Fig. 6 I show the magnesium in coil form arranged in a recess, the fulminate being arranged upon a disk or wad H, which becomes ejected simultaneously with the firing of the fulminate. 90

Fig. 7 is a similar view to Fig. 6, the magnesium being applied to the recess in bulk.

What I claim, and desire to secure by Letters Patent, is—

1. In combination, a projectile, an illuminating means carried thereby, and means embedded in said projectile for igniting said illuminating means. 100
2. In combination, a projectile, an illuminating means carried thereby, and means embedded in said projectile for igniting said illuminating means.

nating means carried thereby, and a rod embedded in said projectile for causing the igniting of said illuminating means.

3. In combination, a projectile, an illuminating means carried thereby, a rod embedded in said projectile, and a fulminate engaged by said rod for igniting said illuminating means.

4. In combination, a projectile, an illuminating means carried thereby, a rod embedded in said projectile, a time-fuse for igniting

said illuminating means, and a fulminate for the said time-fuse adapted to be struck by the said rod.

In testimony whereof I have hereunto set my hand in presence of two subscribing witnesses.

ANTHONY BERNARD TUBINI.
